PATTERN FOR MOLDING ORNAMENTAL
PLASTIC VENEER

Francis J. Gedminas, Philadelphia, Pa.

Application May 19, 1949, Serial No. 94,208

3 Claims. (Cl. 25—118)

1

My invention relates to a device for forming plastic veneer upon walls or surfaces for simulating stone, bricks, blocks, or the like.

An important object of the invention is to provide a device which will permit of the veneered surface having an ornamental or colored coating, without applying the same to the artificial mortar joints.

A further object of the invention is to provide a pattern, for producing the design in the veneer, which pattern is of simplified construction and has a large range of adjustments for producing different shapes.

A further object of the invention is to provide a pattern which is flexible and may be applied to a flat or curved wall surface.

Other objects and advantages of the invention will be apparent during the course of the following description.

In the drawings, forming a part of this application, and in which like numerals are employed to designate like parts throughout the same,

Figure 1 is a fragmentary side elevation of a wall preparatory to applying the plastic veneer;

Figure 2 is a side elevation of the assembled pattern, parts broken away;

Figure 3 is a side elevation of the plastic veneer after being applied to the wall, the assembled pattern being in place, parts broken away;

Figure 4 is a transverse section taken on line 4—4 of Figure 3;

Figure 5 is an enlarged side elevation of one of the pattern strips;

Figure 6 is a transverse section taken on line 6—6 of Figure 2;

Figure 7 is a side elevation of the completed plastic veneer, with the pattern removed, parts broken away;

Figure 8 is a side elevation of the plastic veneer showing the pattern in place therein and adjusted to form a brick or block design, parts broken away, and

Figure 9 is a transverse section taken on line 9—9 of Figure 1.

In the drawings, wherein for the purpose of illustration is shown a preferred embodiment of my invention, the numeral 10 designates a vertical wall which is illustrated as formed of wood, although it may be formed of other suitable material. Secured to the outer face of this wall by any suitable means, such as staples is a foraminous metal sheet 11, which may be a wire mesh or expanded metal lath.

In accordance with my invention, I provide a pattern which includes a plurality of strips 12,

2

13 and 14, which are identical except that they vary in length. Each strip is provided at its ends and throughout its entire length with holes 15 which extend through the outer face of the strip but terminate short of its inner face, and these holes are equidistantly spaced. Each strip is tapered in cross-section and decreases in width inwardly, providing inclined sides 16, and outer and inner faces 17 and 18, which are parallel and vertically disposed in use. These strips are adjustably and detachably connected by staples 19 which are interchangeable and adapted for insertion within the holes 15, and are readily removable therefrom. The staples project outwardly beyond the outer faces 17 so that they may be conveniently manipulated. The strips are preferably formed of rubber reinforced with fabric and are somewhat flexible, which will permit them to be applied to a flat wall or to a curved surface like a cylindrical pillar. Figure 2 shows the strips assembled and connected for producing a rough cut stone pattern.

In the practice of the method, a plastic veneer 20 is applied to the foraminous sheet 11 secured to the vertical wall 10. The mix for the plastic veneer is suitably stiff so that it will not slouch prior to setting. This plastic veneer may contain a mixture of sand, sodium chloride, lime and water, the volumes being optional except that the mix shall be suitably stiff, for the purpose stated. Any other suitable mix may be employed. The veneer 20 is applied by trowelling or the like. After the plastic veneer 20 is thus applied to the vertical wall, the individual pattern strips are pressed into the plastic veneer 20, and arranged to produce the desired design. The design shown in Figures 2 and 3 simulate rough cut stone. The strips 12 may be generally horizontally arranged while the strips 13 and 14 may be diagonally arranged. After the strips are pressed into the veneer 20 so that their outer faces are substantially flush with the outer face of the veneer, the strips are connected by the staples 19, which are forced into selected holes 15. It is obvious that since the holes extend throughout the entire length of the strips and are equidistantly spaced, the strips may be arranged in varied relation to each other. By connecting the strips they produce a unitary pattern. The assembled and connected strips constituting the pattern may be held stationary in position, by any suitable means, such as wood strips S held in place by clamps. The unitary pattern thus held in place will oppose any slouching tendency of the veneer, before it sets. The outer face of

the veneer with the pattern strips embedded within the veneer may be suitably worked by the conventional trowel or by a vibrating trowel. If it is desired to provide the veneer 20 with an ornamental face, crushed stone, or crushed glass or the like, is applied to the outer face of the veneer, before it sets and while the pattern is in place, and this face worked into the veneer. The crushed stone or the like may be applied by trowel or an air blast containing the crushed stone therein. Instead of applying the solid particles to the outer face of the veneer, such outer face may be colored or tinted by paint or like material. The advantage in applying the coating to the outer face of the veneer, while the pattern is still in place, is that the coating of solid particles or paint is kept out of the grooves formed by the pattern strips. The veneer is then allowed to set or harden, after which the pattern strips are individually disconnected from each other by the removal of the staples, and separated from the set veneer, providing grooves 22 having the design of the pattern and simulating mortar joints. The outer face of the veneer will then simulate irregular cut stone having mortar joints.

I may provide a pattern for producing a veneer having a design simulating laid bricks or blocks, Figures 8 and 9. When this is desired, I provide long continuous horizontal strips 12' corresponding to the strips 12 and vertical short strips 14' corresponding to the strips 14, arranged at right angles to form the brick or block patterns. The strips 12' and 14' are identical with the strips 12 and 14 except that they are of different lengths. The strips 12' and 14' have the same holes 15 and are connected by the same staples 19. The veneer 20 is applied to the wall 10, Figures 8 and 9, in the same manner as described in connection with the first form of the invention. If desired, the outer face of the veneer 20, having the brick or block design, may be coated with the ground rock, glass or the like, or painted, while the pattern strips are in place. After the veneer 20 has set, Figures 8 and 9, the pattern strips 12' and 14' are removed, leaving the grooves 22' corresponding to the grooves 22, and the completed veneer will simulate laid bricks or blocks having mortar joints.

Since the strips constituting the patterns are flexible, these strips may be applied to curved surfaces having the veneer secured thereto, as when the veneer is mounted upon a circular pillar or the like.

It is to be understood that the forms of my invention herewith shown and described are to be taken as preferred examples of the same, and that certain changes may be made in the order of the steps of the method, and that changes may

be made in the shape, size and arrangement of the parts of the pattern.

Having thus described my invention, I claim:

1. A pattern for producing a plastic veneer simulating units having mortar joints comprising generally longitudinal pattern strips provided in their outer faces with longitudinally spaced openings, transverse pattern strips arranged between the generally longitudinal pattern strips and provided in their outer faces with spaced openings, and U-shaped connecting staples including spaced legs journaled in selected openings of the generally longitudinal and transverse pattern strips, the staples having outer ends connecting the legs and disposed adjacent to the outer faces of the pattern strips.
2. A pattern for producing a plastic veneer simulating units having mortar joints comprising generally longitudinal pattern strips provided in their outer faces with longitudinally spaced openings, transverse pattern strips arranged between the generally longitudinal strips and provided near their opposite ends and in their outer faces with openings, and U-shaped connecting staples including spaced legs journaled in selected openings of the generally longitudinal pattern strips and in the openings of the transverse pattern strips, the staples having outer closed ends connecting the legs and disposed adjacent to the outer faces of the pattern strips.
3. A pattern for producing a plastic veneer simulating units having mortar joints comprising generally longitudinal pattern strips which are tapered inwardly and provided in their outer faces with longitudinally spaced openings, transverse pattern strips arranged between the generally longitudinal pattern strips and being tapered inwardly and provided in their outer faces with spaced openings, and U-shaped connecting staples including spaced legs journaled in selected openings of the generally longitudinal and transverse pattern strips, said staples having outer closed ends connecting the legs arranged adjacent to the outer faces of the pattern strips.

FRANCIS J. GEDMINAS.
